GIRDLE

Arthur Goldstein, 136 Madison Ave., New York, N.Y.

Filed Jan. 4, 1960, Ser. No. 58,896

Term of patent 14 years

(Cl. D20—2)

The shade lines in the drawing are to show the effect resulting from greater density of a two layered elastic fabric.

I claim:

The ornamental design for a girdle, substantially as shown and described.
